UNITED STATES PATENT OFFICE.

HENRY C. HERCHELRODE, OF DAYTON, OHIO, ASSIGNOR TO A. C. MARSHALL
AND HENRY C. GRAVES, OF SAME PLACE.

HORSE-RAKE.

SPECIFICATION forming part of Letters Patent No. 225,602, dated March 16, 1880.

Application filed September 5, 1879.

To all whom it may concern:

Be it known that I, HENRY C. HERCHELRODE, of Dayton, in the county of Montgomery and State of Ohio, have invented certain new and useful Improvements in Horse Hay-Rakes; and I do hereby declare the following to be a full, clear, and exact description of the same.

My invention relates to that class of horse hay-rakes in which ratchets on the wheel-hubs, and revolving therewith, are employed to elevate the rake-head by the progressive motion of the machine and at the will of the driver.

My improvements consist in the employment and arrangement of certain novel devices for causing the teeth to be automatically raised to discharge the collected loads at the will of the operator, as will be herewith set forth, and specifically claimed.

In the accompanying drawings, Figure 1 is a plan view of a horse hay-rake containing my improvements. Fig. 2 is a side elevation of the same through the line *xx* of Fig. 1. Fig. 3 is a front elevation of the machine. Fig. 4 is an enlarged view of my improved adjustable dog and its attachments.

The frame-work of the rake may be of the ordinary or any suitable construction.

The tilting wooden axle *A*, which in this instance is the rake-head, is hung by spindles to the hubs of the supporting and carriage wheels *B*, and the rake-teeth *C* are attached to this head in any suitable way, either by separate metal castings or by clamping their ends between the head and a retaining-strip, as shown in the drawings.

The thills *D* are united at their rear ends by the cross-bar *E*, from which the cleaner-sticks *F* project in the usual manner, as shown. *G* and *H* are the ordinary cross-bars, which support the driver's seat *I*. This frame-work, consisting of the thills, cross-bars, and their attachments, is connected to the rake-head or axle by means of the strap-hinges *J*, which project from the cross-bar *E*, and are pivoted in any suitable way to the axle. In this instance these pivoted points coincide with the axes of revolution of the carriage-wheels.

The wheel-spindles *a* are clamped between two castings, *b* and *c*, to the under side of each end of the rake-head *A*, and from which they

project to receive the hubs of the wheels. The casting *b* has ears *d* formed integral with it, which ears are flush with the ends of the head *A*, and serve as supports, to which are bolted the shields or casings *K*, as shown. These shields are cylindrical metal drums, with their outer ends open, and are of sufficient diameter to receive the ratchet-wheels *G'*, which are concentric with the wheels *B*, and are bolted or otherwise fastened with an intervening disk, *f*, to the wheel-hubs. The disks *f* serve as covers to the open ends of the drums or shields *K*, as indicated.

Upon each end of the upper side of the head *A* are fastened castings *g*, provided with bearing-ears, as shown, and upon the upper side of the head, at or near its middle, is a casting, *h*, of the shape shown, also provided with ears. These bearings at the ends and center of the head *A* support a torsion-rod, *L*, carrying upon each end a dog, *j*, of the shape shown, which can be thrown into gear with the inclosed ratchets by means of an opening in the periphery of the drum.

Between the ears of the casting *h* is a slotted arm, *l*, of the shape shown, which is keyed or otherwise rigidly fastened upon the torsion-rod; and the torsion-rod may be either one entire rod, running through the arm *l*, or it may be divided, as in this instance, with its inner adjacent ends secured in said arm. A chain, *m*, extends from the upper end of the arm *l*, and is fastened to the seat-beam, as shown, and the arm *l* is held back in the position shown in Fig. 2 by means of a spiral spring, *n*, 85 recessed in the lower front part of the bracket *h*, and bearing against a projecting lip, *o*, which forms part of said arm *l*, as shown. In the rear part of the same bracket *h* is pivoted a gravitating-latch, *p*, which inclines forward 90 and passes through the slot or opening in the arm *l*, as represented. There is a notch cut in the under edge of this latch, which, when the arm *l* is drawn forward by the driver's pressing his foot upon the chain, catches over the lower edge of the slot or opening in the arm, and thus holds it locked. Drawing the arm *l* forward, as thus described, turns the torsion-rod and brings the dogs upon its ends into engagement with the ratchets, and thus effects a lock 100.

between the rake-head and the carriage-wheels. As the wheels continue to revolve the rake-head participates in the motion and the teeth are elevated. When the teeth have been carried up 5 sufficiently to discharge the collected load the nose of the latch *p* comes in contact with a projection, *k*, or any stop placed upon the cross-bar *E* or other adjacent part of the framework, and is forced out of engagement with the arm *l*. The arm *l*, being thus released, is forced back to its normal position by the spring *n*; and, as the dogs are connected with this arm by the intermediate torsion-rod, they are lifted 10 out of engagement with the ratchets, and the rake-head and the teeth being thus freed from the wheels, they are brought by their gravity 15 back to raking position.

The novel and essential feature of my invention is illustrated in Fig. 4; and it consists in 20 providing for the adjustment of the dogs upon the torsion-rod in the following manner: The outer projecting ends of the torsion-rod are made square or polygonal in section, and over this portion is first slipped the sleeve *s*, having a coincident bore. This sleeve carries upon 25 its inner end a disk or flange whose outer margin is notched or serrated, as shown. The inner face of the dog is similarly notched or serrated, as seen, and when it is slipped over 30 the sleeve *s* the two notched faces come together and form a lock. A nut, *t*, screwed upon the end of the rod, which is threaded, holds the serrated faces together. By loosening 35 this nut sufficiently to disengage the serrated faces the dog can be adjusted as desired, and then can be clamped, as before described. This is a very essential feature to the practical working of a rake having a torsion-rod to throw

the dogs into engagement with ratchets upon the hubs, for even should the dogs be properly 40 adjusted in the shop the torsion-rod may lose some of its elasticity by use and a new adjustment of the dogs would be required.

By my device any farmer can regulate the machine in the field. 45

M represents the usual slotted guide-bar, attached to the head at its rear in the usual way; and if desired the machine may have a hand-lever, which can be used independently of the automatic dumping devices. 50

I am aware that it is not new to employ a torsion-rod for effecting the engagement of the dogs with the ratchets and for securing the elevation of the teeth whether the machine is advancing or turning; but 55

What I claim as new, and desire to secure by Letters Patent, is—

1. In a horse hay-rake, the combination, with ratchets revolving with the carriage-wheels, and a torsion-rod mounted on the rake-head, of dogs made adjustable upon the ends of 60 said rod, whereby the relations of the parts enumerated can be adjusted when desired, as set forth.

2. The dogs *j*, having serrations or detents 65 on their inner faces, in combination with disks or collars secured to the ends of the torsion-rod and having coincident serrations or detents, as set forth.

Witness my hand this 28th day of August, 70
A. D. 1879.

HENRY C. HERCHELRODE.
